UNITED STATES PATENT OFFICE

2,239,434

COIN OR CHECK DISPENSER

John C. Wahl, Chicago, Ill., assignor to Lion Manufacturing Corporation, Chicago, Ill., a corporation of Illinois

Application August 24, 1938, Serial No. 226,437

13 Claims. (Cl. 133—5)

The invention relates to a slide type of coin, check or coupon dispenser.

These mechanisms, useful with coin handling apparatus such as change-makers, comprise a stack of horizontal, superimposed slides formed with vertically aligned openings that serve to hold a vertical column of coins or the like which are to be dispensed upon movement of a selected slide or slides, taking them in order from the bottom up to vary the number of coins dispensed or ejected; it being understood that when a slide shifts a coin, said coin is dropped by gravity through an offset discharge opening.

More particularly the present invention relates to improvements for such type of dispenser; it being desirable to provide a simple fool-proof structure capable of easy production at reasonable costs; to provide novel operating mechanism for the slides to overcome certain difficulties heretofore encountered because the stack of coins in the aligned slide openings did not remain in perfect column relationship; to provide means preventing jamming of the slides because of coin inequalities; and lastly, generally to improve the structure and operation of these mechanisms.

The main object of the invention is to provide such a pay out device having an improved construction of coin ejecting slides.

Another object is to provide an improved main, lower slide with means for conjointly setting for operation the other slides.

It is also an object to provide an improved guide means for the ejector slides.

Another object is to provide an improved slide type pay out device in which the slides are spring pulled when ejecting coins; improved means being provided for cocking the slides preparatory to their operation, so that a snappy cocking movement of the slides results and cannot drag the column of coins and cause them by inertia to slough over and get out of vertical line, such result being possible since the coin apertures in the slides are of larger diameter than the coins.

Another object of the invention is to provide improved means for preventing worn coins from accidentally jamming the slides as they are pulled to pay out position.

Other important objects will no doubt become known as the disclosure is more fully made.

Briefly, the improved dispenser comprises a base plate on which is carried for sliding movement, a lower or main pay out slide, and thereabove are positioned additional, independent pay out slides. All slides have a coin receiving open-

ing which openings align vertically to retain a column of coins or checks. Individual springs serve normally to pull the respective slides to ejector or pay out position, which position is offset from the position occupied by the vertical column of coins in the slides. Improved operating mechanism is initiated into action to engage a part on the lower slide which part extends upwardly through slots formed in the upper slides, said part being very suddenly moved by the operating mechanism to shift all slides simultaneously to a cocked position. This sudden movement keeps the coins in the column from getting out of vertical line, since the coin openings in the slides are of greater diameter than the coins. The bottom slide is positively locked in cocked position by a part of the operating mechanism, and the upper slides are individually locked by respective pivoted latch levers. When the operating mechanism works, means forming part thereof causes release of the lower slide for spring pulled operation to dispensing position. The upper slides, considering them in order from the bottom up, may be selected for operation with the main lower slide when their respective latch levers have been released. In this manner the number of coins to be dispensed can be varied. Such variation is further accomplished by suitably varying the thickness of the coin moving ends of the slides. Each slide has a novel spring detent means associated with it to prevent accidental trailing or sloughing off of an extra coin with the slide when it pays out to prevent jamming and damage. Incidental features are the provision of slide guide means and the special sheet metal structure of the slides. So much will suffice for the time being in presenting a general understanding of the improved structure, which is illustrated in detail in the accompanying sheets of drawings, wherein:

Figure 1 is a general side elevational view of the coin or check dispenser, including the operating mechanism therefor;

Figure 2 is a similar view taken from the opposite side;

Figure 3 is an end view of the structure;

Figure 4 is a detail, plan view of the lower or main slide;

Figure 5 is a side detail, elevational view of the same slide, looking from the line 5—5 of Figure 4;

Figure 6 is a top plan view of the dispenser structure, per se;

Figure 7 is a top plan view of the same struc-

ture with the cover plate removed to expose the under parts;

Figure 8 is a plan view of an auxiliary dispenser slide;

Figure 9 is a side view of the same slide;

Figure 10 is an enlarged, plan sectional view of the auxiliary slide structure, taken along the line 10-10 of Figure 9, looking in the direction of the arrows;

Figure 11 is a cross sectional view through the slide structure taken along the line 11-11 of Figure 10, looking in the direction of the arrows; and,

Figure 12 is a section along line 12-12 of Figure 6, looking in the direction indicated.

The improved mechanism, in practice, may be associated with a suitable housing structure not shown, the pay out unit per se embodying a base plate 15 which is generally elongated and rectangular, with opposite side frames thereof comprising upright side walls 16 secured thereto. The base plate at one end is formed with a coin drop hole 17. Opposite edges on the upper surface of the plate 15 are notched as at 18.

Carried at the discharge end of said plate 15 are four corner posts 19 and at the opposite end thereof is a single central post 20. Slidably mounted on the base plate is a main pay out slide 21 shown in Figure 4, the same having a large head 22 formed with a coin receiving hole 23 and at its opposite end are provided opposite ears carrying blocks 24, normally positioned proximate the notches 18 in the base plate 15. At its center, as seen in Figure 5, the slide carries a rigid bar formed with an upstanding, sturdy post 25. The slide 21 is also formed with a long slot 26 including an abutment shoulder 27. One wing 24 carries an upright pin 28 to which is connected a spring 29 having its other end connected to a pin 30 mounted rigidly on the base plate 15. It will be noted that the post 20 extends upwardly through the slot 26 in the main slide 21 when the latter is in position on the base plate. The slide 21 also carries an abutment block 31. This slide in practice may be of a thickness at its end 22, equal to the thickness of three coins so that its opening 23 may hold these three coins as will appear.

The corner posts 19 carry spacer collars 32 and side spacer bars 33, the height of the collars being varied as desired properly to space a series of superimposed auxiliary pay out slides 34, all of the type shown in Figures 8 to 11, inclusive. In the present form, five of such slides are utilized.

Each slide 34 has an enlarged head portion 35 with a coin hole 36 therein and opposite guide ears 37 which fit in between the side spacer plates 33 in an obvious manner. Each slide 34 is of light weight sheet metal construction and includes a long end slot 38 with an abutment notch 39 to correspond with a similar conformation in the main or bottom slide 21. Further, each slide 34 has a long central slot 40 through which the post 25 heretofore described extends upwardly. These slots 40 in all slides 34 register vertically. One side edge of each slide 34 has a pair of spaced notches 41 and 42. Further, each said slide 34 has a lateral apertured ear 43 at the end remote from its head end, and separate coil springs 44 connect respectively with each said ear 43 and a post 45 carried on the base plate 15. The side edges of the slots 38 guide in grooves formed in the post 20.

The head end of each slide 34 is specially

constructed and includes a central upstanding tang or nib portion 46 at the front edge of the coin hole 36. Auxiliary head plates 47 and 48 are fastened by rivets 49 or by welding if desired,

5 to the under side of the head part 35 as shown in Figures 9, 10 and 11. These extra plates have holes 36' formed in them in registration with the hole 36 in the slide 34, heretofore described.

The hole 36' in the plate 48 as shown in Figures 10 and 11 has an extension slot 36'' slightly wider than the width of the coins used. On opposite sides of hole 36' each plate 47 is notched as at 50 in which opposite notches are positioned, flat detent springs 51 having portions provided

15 by an angle in them, to extend slightly into the openings 36' and slot 36'' in such a manner that the two opposed angle portions in effect form yieldable obstructions across the slot 36'' and the front end of the holes 36'. This space between the angle portions of the springs in the slot 36'' is less than the diameter of a coin handle, so that in the event an extra, thin or worn coin has a tendency to creep along or slough off with the correct number of coins to be moved by a lower slide structure in the payout movement thereof, it will have its movement yieldingly resisted and, in fact, stopped by these springs 51 in the next preceding slide thereabove which is not released, so that such extra coin will on the return or cocking stroke of the slide be pushed back into the column by the nib 46. Each notch 50 as clearly shown in Figure 10 has a lengthwise extension slot into which is respectively snap fitted the bent back leg portion of each spring 51, thereby holding the springs 51 with a snap fit in the plate portion 47. This situation arises sometimes when a lower slide is moved to perform its dispensing operation and then the springs 51 in the slide next thereabove can function, as stated; that is, when such immediate upper slide is held locked and does not move to dispensing position. Thus on the payout stroke the relieved portion or slot 36'' permits a coin that is thin or tends to cock to enter the slot 36'' to be yieldingly held by the springs 51 and on the return stroke the nib 46 frees the yieldingly held coin and moves it back into the column. Each plate 47 on each auxiliary slide includes a rigid front, slotted extension 52, the slots thereof being centrally located to form a space above each tang 46 on the next lower slide. This provides at all times for free relative sliding movement between adjacent slides.

Some coins or checks due to wear are thinner 55 than others so that when stacked in column formation in the aligned holes 36 they may not even register or line up with the slides, it being understood that each slide head is of a thickness to handle its allotted number of normal thickness coins or checks when it cuts through the stack. If a thin coin is in the stack, then naturally coins thereabove will not truly register or line up with the slides thereabove. For that reason it happens that a thin coin creeps along with the correct number of coins to be handled by a slide, as an extra coin, or due to misalignment of coins in the stack because of the presence therein of a worn coin, a normal thickness coin can be dragged along with a slide, thus creating the sloughing off condition, which the novel structure of this invention compensates to prevent jamming.

At the side of the pack of slides, the base 15 carries an upstanding guide bracket 53 shown in Figure 1, which bracket has spaced length-

wise, parallel slots 54 formed therein, the slots generally being spaced to conform to the spacing of the auxiliary slides 34. This guide bracket occupies a position on the base 15 between the ends of the latter, as shown. At the end of the base, remote from the coin discharge end thereof and on the same side as the bracket 53, the base carries a vertical shaft 55 with appropriate spacers 56 (see also Figure 7) for pivotally mounting intermediate their ends and in spaced relation, a series of latching levers 57, which are horizontally disposed.

Each latch lever 57 has a hooked end 58 to which is attached a pull spring 59 in turn connected to hook portions 60 on a bracket 61 rigidly mounted on the opposite side of the base 15. The other portions of said levers 57 extend alongside the respective slides 34 and include outwardly bent ends 62 extending respectively through the slots 54 in the bracket 53. In fact, the intermediate portion of each lever 57 overlies a slide 34 as shown in Figure 7. Each such portion of each lever includes a downturned abutment or boss 63 extending down into the slot 38 of the slide therebelow and by means of the springs 59 normally engaging and cooperating with the abutment notch 39 to lock the slide 34 against movement. A latch lever 57 is also provided similarly for the main slide 21.

On the opposite side of the slides from bracket 53 the base 15 at an intermediate portion carries a vertical shaft 64 on which is pivoted a lever 65 having a wide latch portion 66 to engage in the notches 41 and 42 of slides 34 and cooperate with boss 31 of the slide 21 to act as a stop, said lever latch being pulled to engaging position by a spring 67 connected between it and the base as seen in Figure 2. The opposite end of the lever 65 carries a cam 68.

The whole slide assembly is held together by a cover plate 69 shown in Figure 6, which plate is held down by screws 70 passed into the posts 19 and 20, said plate having a coin receiving opening to register with the holes 36 and 36', and also a slot 71 to register with the slots 40 so that the slide cocking post 25 may extend up through the cover plate 69. The discharge or front end of the cover 69 is cut out as at 72 and the top slide 34 at said end carries an upstanding rigid bracket 73 extending above the cover 69 for a purpose to appear.

The operating mechanism for the pay out structure will next be described, reference especially being had to Figures 1, 2 and 3.

The sides 16 carry a cross shaft 74 on which is fixed for rocking movement therewith, a bell crank lever 75 in turn carrying a pin 76 adapted to have connected thereto some suitable operating link, which in a well known manner may form a part of a coin operated machine with which the dispenser structure of this invention may be used. Such machine is disclosed in Mills' Patent No. 1,912,992 of June 6, 1933. The other end of said bell crank 75 carries another pin 77 which cooperates with and fits into a notch 78 formed in one end of a lever 79 carried fast on a cross rock shaft 80 carried in the sides 16 parallel with the other shaft 74. This lever 79 has an upward extension formed with a laterally disposed boss 81. Said lever 79 also has an arm 82 formed therewith to one end of which is connected a coil spring 83.

Positioned loosely on the shaft 80 closely adjacent the lever 79 is another lever 84 the upper end of which has the other end of the spring 83

connected thereto, the spring holding the loose lever 84 pressed against the boss 81 on lever 79. The lever 84 has a downwardly extended tail portion 85 positioned to cooperate with the upright post 25 of the main slide 21 in a manner presently to appear. One end of the shaft 80 also has made fast thereto a depending lever 86 positioned to cooperate with the cam 68 on the lever latch 65.

A third cross shaft 87 is journaled in the sides 16 for both rocking and axially shifting movement, the means accomplishing the axial shifting movement being well known and part of the coin operated machine, not shown. Secured to the shaft 87 to move therewith is a depending lever arm 88 having an arcuate tail portion formed with steps 89 (Figure 1), there being one notch or step portion for each end 62 of the respective latch levers 57. When the shaft 87 rocks normally this stepped arm 88 swings clear of the tails 62 on the levers 57; but when the shaft 87 is shifted axially then the steps 89 will engage one or more tails 62 to release the levers 57 depending upon the extent of rocking movement of lever 88. In this fashion release of the pay out slides is controlled. The ends 62 form a vertical column which ends may be respectively engaged by the steps 89. Thus axial movement of the steps 89 will effect release of any slide, it being understood that all slides below the released slide would be released at the same time.

One side member 16 carries a hinge pin 90 (see Figure 3) on which is pivoted a large bell crank lever having a long upstanding arm 91 with a pin 92 thereon, and a long rearwardly extending arm 93 having a notch 94 therein and an abutment portion 95 at its free end. This completes the details of the description and the operation of the improved mechanism will next be given.

The arm 93 constitutes a lock arm in that its end 95 engages the boss 24 on the main slide 21 and holds it locked. When the coin operated machine is properly coin released, means not shown, but well known in the art will push on pin 92 to raise the arm 93 to free the slide 21. At the same time some part of the machine will rock the shaft 74 and swing the bell crank 75 in the direction of the arrow in Figure 2, causing the pin 77 to rock the lever 79 with the shaft 80. The arm 82 therefore pulls on spring 83 to stretch same. At the same time the stop boss 81 moves away from the upper part of the loose lever 84. Next the tail 85 of this lever abutting the upright post 25 presses thereagainst with increasing force as the tension of spring 83 increases, but the slide 21 carrying the post 25 cannot be moved by the tail 85 since the slide 21 is locked by the latch 66 engaging the block 31. At the same time the arm 86 turns with the shaft 80. When the spring 83 has been properly tensioned the arm 86 has reached a position where it strikes the cam 68 to release the latch 66 from the slide 21 as well as from the notches 41 in all of the upper slides 34.

With all slides now released and the lever 85 bearing strongly against the post 25 the slides 21 and 34 as a group are forcibly and quickly driven to cocked position, which position is shown in Figures 1 and 2, because the post 25 engages in the end of the slots 40 to move all slides together. When the slides are all in fully cocked position the portions 63 on the latches hook over the respective shoulders 27 and 39 of the slides to hold the slides latched in such cocked positions. At this time all of the springs 44 and 29 are stretched.

As has been said the coins are in a vertical column in the alined holes 36, 36' and 23 in the respective slides, the bore thus formed through the pack of slides being of greater diameter than the diameter of an alined stack of the coins in said bore. In other words, the coins are smaller in diameter than the coin receiving holes in the slides. Such stack of coins rests on the base plate 15 as can be understood from the showing in Figure 12. The snappy cocking action of the drive force on the suddenly released lower slide post 25 has the effect of overcoming any lag or inertia tendency of the stack of coins so that they move cleanly as a column without sloughing over or dragging. This prevents cocking of coins in the coin slide holes and serves in a great measure to prevent jamming when ejector or dispensing action takes place. When the slides have all been cocked in their shifted position, as described, the operating parts 75, 79, 84 and 86 return to inoperative position ready for a subsequent operation.

The release of the slides 21 and 34 from the bottom up, in successive order depends upon the operation of the stepped member 89 which rocks with the shaft 87. These steps 89 serve when the member carrying same is axially shifted with said shaft 87 to engage and push against the tails 62 of the latch levers 57, whereby to move said levers inwardly to release the parts 63 thereof from the notch in the slides. This permits the drive spring 29 for the lower slide and the springs 44 for the upper slides to pull said slides to dispensing position over the hole 17 in the base 15 to drop the moved coins from the pay out device. The functioning of the stepped member 89 is well known in the art and forms no part of the present invention, it being sufficient to say that its steps when in position in relation to the latch lever tails 62 engage the tails and push same inwardly in successive order from the bottom upwardly depending upon how many of the coin ejecting slides it is determined shall be operated. If a slide higher up in the stack is released then all those below it will be released at the same time. Each slide in this disclosure at its coin carrying end is of a thickness to move three coins from the stack. The pay out stroke of each slide is limited by the end of the slots 26 and 38 striking the guide post 20.

In the event a worn, thin coin tries to slough off between a moving slide and the locked slide immediately thereabove, the springs 51 and tang or nib 46 act to prevent such result, thereby further preventing coins from jamming. After one or more slides have been released to dispensing operation in order from the bottom up, the slides have to be reset to cocked position by again operating the coin machine mechanism disposed above the pay out device in the manner previously described.

When all slides are successively released to pay out position including the top slide 34, then the bracket 73 is moved to engage some auxiliary means not shown for any purpose desired.

From the description above given it will now be clear that an improved structure for the purposes stated has been provided. It is the intention to cover herein all changes and modifications which do not depart from the spirit and scope of the invention as defined in the following claims.

What is claimed is:

1. In a coin dispenser, a base, a main slide and auxiliary slides, said slides arranged in a stack

and having registerable coin receiving openings to contain a column of coins supported on the base, the lower slide carrying an upright post passed through registered slots formed in the auxiliary plates, individual springs tending to pull the respective slides toward a pay out opening formed in the base offset from the column of coins, means to engage the post to move same with all the slides to a cocked position with the springs tensioned, means for individually latching the slides in such position, and means for individually releasing any slide and slides as may be below it to cause said slides to move coins to the pay out opening.

2. In a coin dispenser, a base, a main slide and auxiliary slides arranged on the base in a stack with the main slide at the bottom and all slides having alinable coin holding openings to receive a column of coins standing on the base adjacent an offset discharge opening in said base, an upright post carried on the main slide and the other slides having slots to receive the post, springs tending to pull the slides toward the offset opening, other slots formed in the slides including a notched part, latch members yieldingly respectively engageable in said latter part to hold the slides in a cocked position with the springs stretched, and means engageable with the post to move the main and auxiliary slides to their cocked latched position.

3. In a coin dispenser, a base, a main slide and auxiliary slides arranged on the base in a stack with the main slide at the bottom and all slides having alinable coin holding openings to receive a column of coins standing on the base adjacent an offset discharge opening in said base, an upright post carried on the main slide and the other slides having slots to receive the post, springs tending to pull the slides toward the offset opening, each slide having an abutment shoulder formed thereon, pivoted latch members carried on the base and having portions engageable with the shoulders respectively to hold the slides in a cocked position with the springs stretched, and means engageable with the post to move the slides together to their cocked latched position.

4. A coin dispenser having a base, a stack of horizontal slides having alinable coin holding openings surrounding a column of coins on the base offset from a discharge opening formed therein, the lower slide having an upright post passed up through slots formed in the slides thereabove, springs for pulling the slides toward the discharge opening, means to move the post and all slides therewith to a position away from the discharge opening to stretch the springs, and means releasably latching the slides in the latter position.

5. A coin dispenser having a base, a stack of horizontal slides having alinable coin holding openings surrounding a column of coins on the base offset from a discharge opening formed therein, the lower slide having an upright post passed up through slots formed in the slides thereabove, springs for pulling the slides toward the discharge opening, means to move the post and all slides therewith to a position away from the discharge opening to stretch the springs, means releasably latching the slides in the latter position, each slide having another slot therein, said latter slots registering in the several slides, and a guide post on the base passed through said latter slots to guide the slides and hold same in fixed relative positions.

6. A coin dispenser having a base, a stack of

horizontal slides having alinable coin holding openings surrounding a column of coins on the base offset from a discharge opening formed therein, the lower slide having an upright post passed up through slots formed in the slides thereabove, springs for pulling the slides toward the discharge opening, means to move the post and all slides therewith to a position away from the discharge opening to stretch the springs, means releasably latching the slides in the latter position, each slide having guide slots formed therein adjacent one end and an enlarged head at the other end with lateral opposite extensions, a guide post fixed on the base and passed through the guide slots, and other guide means cooperating with the lateral extensions to guide the said other end of the slides.

7. A coin dispenser having a base and a stack of slides carried thereon with springs tending to pull same to a coin discharge position, the bottom slide having a post cooperable with the other slides so that when the bottom slide is moved away from discharge position the other slides move therewith to stretch all the springs, means releasably locking the bottom slide, spring power trigger means movable to store energy while bearing against the post with the lower slide locked, means to release the lock and lower slide to cause the trigger means sharply to snap the slides together to a cocked spring stretching position, and means releasably to latch all slides in such position.

8. A coin dispenser having a base and a stack of slides carried thereon with springs tending to pull same to a coin discharge position, the bottom slide having a post cooperable with the other slides so that when the bottom slide is moved away from discharge position the other slides move therewith to stretch all the springs, means releasably locking the bottom slide, spring power trigger means movable to store energy while bearing against the post with the lower slide locked, means to release the lock and lower slide to cause the trigger means sharply to snap the slides together to a cocked spring stretching position, means to guide the slides and limit their movement, and a bank of spring pulled latch levers carried on the base and respectively cooperating with the slides to hold same releasably in the cocked positions.

9. In a coin dispenser, a base, a main slide and auxiliary slides, said slides arranged in a stack and having registerable coin receiving openings to contain a column of coins supported on the base, the lower slide carrying an upright post passed through registered slots formed in

the auxiliary plates, individual springs tending to pull the respective slides toward a pay out opening formed in the base offset from the column of coins, means releasably locking the lower slide, means comprising a spring power lever engaging the post and movable thereagainst with increasing pressure, means releasing the lower slide sharply to move same under such pressure with the upper slides moving therewith to a cocked position, and means releasably to latch all slides in the latter position.

10. A slide for pay out devices comprising an elongated plate having an enlarged head at one end with a coin moving hole formed in the head, a lateral extension at the other end, an elongated slot being formed in the slide at said latter end, and a post secured to the slide between the slot and hole, said slot having an abutment shoulder formed therein and one side edge of the slide having a notch therein.

11. A slide for pay out devices comprising an elongated plate having an enlarged head formed with oppositely extending guide wings, the plate having two elongated slots therein arranged end to end in spaced relation, a side edge of the plate having a notch formed therein and one of the slots being formed with an abutment shoulder.

12. A coin dispenser comprising a stack of slides having springs tending to pull same to dispensing position, each slide having a slot formed with an abutment portion, a bank of pivoted latch members carried adjacent the slides and having means cooperable with the abutment portions to lock the slides in a cocked spring stretching position, and means comprising a member rockable about and shiftable along an axis to engage and release the latch members for freeing any slide with any slide or slides that may be below it in the stack so that the said slides may be moved to dispensing positions.

13. A coin dispenser comprising a base and frame, said base carrying a stack of slides having springs tending to pull same to dispensing position, an upright member on the lower slide engageable with all the other slides, means to lock the lower slide, a shaft carried in the frame, a lever on the shaft to engage the member, and means for applying increasing pressure on the member while the lower slide is locked, means to release the lower slide whereby the said lever under its pressure sharply moves the lower slide and other slides with it to a cocked spring tensioning position, and means to lock the slides in the latter position.

JOHN C. WAHL.
